UNITED STATES PATENT OFFICE.

CHARLES GUILLAUME DIEDERICHS AND MARIE AUGUSTE EUGÈNE MARQUELET, OF STE. COLOMBE LES VIENNE, FRANCE.

MACHINE FOR CLEARING SILK OR OTHER TEXTILE THREADS.

SPECIFICATION forming part of Letters Patent No. 653,174, dated July 3, 1900.

Application filed May 12, 1898. Serial No. 680,480. (No model.)

To all whom it may concern:

Be it known that we, CHARLES GUILLAUME DIEDERICHS, manufacturer, and MARIE AUGUSTE EUGÈNE MARQUELET, engineer, citizens of the Republic of France, residing at Ste. Colombe les Vienne, France, have invented a certain new and useful Machine for Clearing Silk or other Textile Threads, of which the following is a full, clear, and exact specification, reference being had therein to the accompanying drawings.

This invention relates to a machine for effecting the easy and rapid clearing of threads submitted to its action and for freeing them from defective knots, wisps, irregularities in thickness, doublings, &c., and which machine enables us to produce tissues or textiles of great uniformity and regularity, at the same time increasing production and avoiding faults or blemishes.

That our invention may be better understood we have shown on the annexed drawings an elevation, Figure 1, of our machine, and a plan view, Fig. 2.

The thread A unwinds from a spool B, suitably supported, and first passes over a fixed glass rod C, then through the trimmer D, afterward over another fixed glass rod E, and finally, after having passed over a glass rod F, acting as a guide, is wound upon the spool G. The thread-guide rod F, mounted on a lever oscillating or pivoting around an axis f, (see Fig. 1,) directs or guides the thread A in its winding on the spool G. The spool G is mounted on a spool-carrier or winding-spindle g, supported in a bearing adjustable for height. On this spindle g is fixed a pulley g², which engages an endless strap H, passing over drums, such as h, suitably arranged and operated. The pulley g² can be thus driven, and the spindle g consequently receives a rotatory movement. The strap H can be tensioned by the help of a tension-roller h', mounted on a support h², furnished with a bearing or socket h³, of which the position is adjustable for height by means of a set-screw h⁴. The roller-support h' is fixed to a portion of the machine I, which ordinarily is an angle-iron secured upon a support i, fixed on the connecting cross-piece J.

The instantaneous stoppage of the spindle

g can be effected or performed by means of a band-brake K, which may be caused to act on the pulley g² adjacent thereto. The band of this brake is fixed to the end or bottom of 55 the beam L.

The trimmer D is a sort of draw-plate and may be of metal, glass, or agate. It is mounted on a carrier d by means of a plate-spring d', which secures it in place. This method of 60 attachment facilitates the rapid replacing or substitution of trimmers, which are so made as to be interchangeable and are numbered so as to allow a rapid control of the same, with a view to recognizing if the trimmer in position corresponds to the number of the thread. The carrier d can pivot on its axis d², mounted on a support d³, fixed to the cross-piece M, which latter is also furnished with the step-bearing g'. The trimmer and its carrier are 70 balanced by a sliding weight d⁴. To the carrier d is secured a rod N, capable of raising the toggle-levers or hinge O, which acts in its turn on a lever P to cause the throwing into gear of the machine, the disengagement or 75 throwing out of gear, and the brake-action upon or retardation of the spindle. This hinge O is arranged in such a manner that when its two portions o o' are parallel or not inclined at an angle to each other a part or 80 lever l bears upon the arm p of the lever P, pivoted at p' and acting as a guide for the spindle g. This latter is then in such position that the roller g² is in contact with the driving strap or band H. When the rod N 85 is raised, it bears upon the hinge O, so that the two parts of the latter form a more acute angle. The part O leaves the arm p of lever P, which is then acted on solely by a spring p². The pulley g² first separates from the 90 band H and then comes into contact with the part K, acting as a brake, which causes the immediate stoppage of the spindle g. The lever P is pivoted at p' on a support Q, mounted upon the plate or beam L, and its position 95 is adjustable by means of a screw q. The hinge o is fixed to a support o², secured to the beam L, and the position of which is adjustable by means of a screw o³.

To enable the spool G to easily revolve, so 100 as to wind or unwind the thread, it is necessary to provide means for maintaining the

spindle g in an intermediate and free position, the pulley g^2 being in contact with neither the strap H nor the brake K . For this purpose on the lever P is fixed by a pivot r a click or 5 catch R , capable of engaging a notch l' , formed in the beam L and corresponding with the intermediate position of the lever P .

The operation of the machine above described is as follows: The thread A , unwind-10 ing from the spool B , reaches the trimmer D . If a kink, knot, or projection is presented thereto, it raises this latter, which is balanced by its counterweight d^4 . The carrier d is then 15 raised and swings on its axis and raises the rod N . This latter abuts against the under side of the disengagement-hinge O , the two parts of which then form an angle and, ceas-20 ing to maintain the lever P , allow the spring e^2 to pull it over. The pulley g^2 leaving the strap, the spindle is disengaged and is stopped 25 immediately, because the pulley g^2 at once comes in contact with the band-brake K . When a stoppage has been effected and the thread has been put in order, we proceed as 30 follows for the subsequent operations: After having lowered the carrier d on the glass rod C the lever P is replaced in the position in which the pulley g^2 is in contact with the strap H , which rotates the spindle g . This 35 position is insured by the hinge O .

To be able to cause the spool G to turn freely, so as to wind or to deliver or unwind the thread A , we proceed as for the starting; but in place of pushing the lever P to the 35 end of its stroke we stop it opposite the recess l' , Fig. 2, and cause the catch R to engage this notch. The spindle g^2 can then rotate freely. In this position to cause starting we have only to push the lever P , the catch 40 R being raised at the same time out of the recess l' , Fig. 1.

The disengagement-hinge O possesses the great advantage of necessitating only a minimum force to cause disengagement. The result is that our machine suits all kinds of 45 thread, even the very finest. Stoppage is immediate and does not involve a risk of breaking the thread.

To hold the trimmer D , its carrier d is furnished with spring d' , secured thereto by 50 means of rivets. This spring allows the trimmer to be quickly changed or replaced, according to the thicknesses of thread to be wound. The trimmers are preferably numbered, so that we can easily notice if the 55 numbers in place correspond with the numbers of the threads treated.

The number of spindles mounted on the machine is variable. In the portion of the machine shown in plan on Fig. 2 there are three 60 spindles. The first, 1, is in gear, the second, 2, is out of gear, and the third, 3, is in gear.

The mechanism described has been shown in connection with the spindles Nos. 2 and 3.

It should be understood that we may modify 65 the machine above described without departing from the spirit of our invention.

What we claim as our invention, and desire to secure by Letters Patent, is—

1. The combination of the driving device, 70 the winding-spool adapted to engage the same, the lever in which said spool is journaled off the center or fulcrum of the lever, the toggle-levers connected at one end with a stationary support, and at the other with the first-named 75 lever at a distance from its fulcrum, a trimmer through which the thread is adapted to pass, said trimmer being movable by irregularities of the thread, and an operative connection whereby the movement of the trim- 80 mer will actuate the toggle-levers.

2. The combination of the driving device, the winding-spool movable into and out of engagement with said driving device, the hinged or toggle levers connected to the spindle of 85 the spool to shift the same, a trimmer through which the thread is adapted to pass, said trimmer being movable by irregularities of the thread, a spring for drawing the toggle-levers together or keeping them in an extended po- 90 sition, and a tripping-rod actuated by the trimmer to throw the toggle-levers out of the extended position.

3. The combination of the driving device, the winding-spool movable into and out of en- 95 gagement with said driving device, the hinged or toggle levers connected to the spindle of the spool to shift the same, a trimmer through which the thread is adapted to pass, said trimmer being movable by irregularities of the 100 thread, and an operative connection whereby the movement of the trimmer will actuate the toggle-levers.

4. The combination of the winding-spool, driving mechanism on one side thereof, a brake 105 on the other side of the spool, the latter being movable between the driving mechanism and the brake, a trimmer through which the thread is adapted to pass, said trimmer being movable by irregularities of the thread, an op- 110 erative connection whereby the movement of the trimmer will throw the winding-spool from an engagement with the driving mechanism to an engagement with the brake, and means for holding the spool in an intermediate posi- 115 tion.

In testimony whereof we have signed our names to this specification in the presence of two subscribing witnesses.
